UNITED STATES PATENT OFFICE.

JOSEF NICKL, OF OBERNDORF-ON-THE-NECKAR, GERMANY, ASSIGNOR TO WAFFEN-FABRIK MAUSER, AKTIENGESELLSCHAFT, OF OBERNDORF-ON-THE-NECKAR, GERMANY.

RECOIL-LOADING PISTOL.

Application filed June 16, 1921. Serial No. 478,210.

To all whom it may concern:

Be it known that I, JOSEF NICKL, engineer, a citizen of the German Republic, residing at No. 8 of Hauptstrasse, in the city 5 of Oberndorf-on-the-Neckar, Germany, have invented certain new and useful Improvements in Recoil-Loading pistols (for which I have filed applications in Germany, April 17, 1916, Turkey, Sept. 25, 1918, Hungary, 10 Jan. 13, 1920, Poland, March 16, 1920, Roumania, March 19, 1920, and Czecho-Slovakia, Dec. 30, 1919—all in the name of "Waffenfabrik Mauser Aktiengesellschaft of Oberndorf-on-the-Neckar"), of which the 15 following is a specification.

My invention relates to a hammer-actuated recoil-loading pistol with a breech-slide guided on the grip-stock and it pertains more particularly to novel improvements in 20 connection with the trigger-mechanism and the safety device.

The object of my invention is to provide a pistol with a combined trigger and safety mechanism of a simple construction and of 25 efficient and reliable operation. To this end the hammer is provided with a projecting circular rib or flange surrounding or enclosing the actuating nose of the sear and in which a number of notches are provided for 30 the engagement of both the sear nose and the safety lever. The engaging end of the latter is, for the purpose, bevelled or tapered and the notch co-acting therewith for setting the hammer safe is shaped and arranging 35 in a manner that when the pistol is set "safe" by means of the safety lever the hammer is turned backwards by the pressure of the firing pin and thereupon locked in its safety position. The arrangement is 40 such that the mechanism operates with perfect reliability and is protected against the access of dirt and grit in a simple manner.

I have shown in the drawings forming part of this specification, one constructional 45 embodiment of my invention only, but it is to be distinctly understood that my invention is not to be confined to the particular form of the improved mechanisms shown by way of illustration.

50 In the drawings:

Figure 1 is an elevation of the recoil-loading pistol with the improved mechanisms, partly in section and with the hammer uncocked and unlocked.

Figure 2 is a section on the line A—B of 55 Figure 1.

Figure 3 shows a part of Figure 1, but with the hammer uncocked and locked,

Figure 4 is a similar view showing the position of the parts when the hammer is 60 cocked and unlocked,

Figure 5 is a similar view with the hammer locked,

Figures 6, 7 and 8 are side views and a vertical section of the hammer, respectively, 65

Figure 9 shows the safety lever, seen from inside and on top, further a side view and a front view of the lever,

Figure 10 shows a side view, a front view and a top view of the sear, 70

Figure 11 shows the trigger pawl.

The pistol illustrated in the drawings essentially comprises a grip-stop *a* with the handle proper, the breech-slide *b* guided thereon, and the barrel *c* enclosed to the full 75 of its length by the breech-slide.

In the firing position the barrel *c* is locked with the breech-slide in a known manner and after firing the barrel is released or unlocked during the backward movement of the 80 breech-slide, so that the latter runs alone. On its return movement the breech-slide is again locked with the barrel. The hammer *d* acting on the firing pin *e* in the well known manner, has a disk-like hub or nave *r* mounted on a pivot or cross-pin *s* which forms its axis of rotation, and further has a circular rib *f* on said hub or nave, the center of which coincides with the said axis. The rib or flange *f* encircles or surrounds the nose 90 *i* on the sear *j* and is cut out to form four circumferential notches of which two, *g* and *h*, serve for the reception of the nose *i*, whilst the other two notches, *k* and *l*, serve for the engagement with the safety lever *m*. The 95 sear *j* is operated in a known manner by a trigger pawl *o* pivotally mounted in the trigger *n*, so that when the hammer is cocked and a pressure is exerted on the trigger the sear is released from its position in the cocking notch *h* of the hammer and remains in a released state to allow the hammer to rotate, until the releasing pawl *p* is moved downwards in the well-known manner by the impact or pressure of the recoiling breech-slide 100 to disengage the trigger pawl from the sear.

The safety lever *m* is pivotally mounted in a known manner within the gripstock and

is provided at its rear end with an inwardly projecting nose *q* so bevelled as to be adapted to engage the notches *k* and *l* of the hammer. The notch *k* for locking the uncocked hammer in safety position is located with relation to the nose *q* of the safety device so that when the pistol is put safe, that is to say, when the safety lever *m* is moved into the position shown in Figure 3, the nose *q* engages in the notch *k* of the hammer and causes the hammer to turn back from the position illustrated in Figure 1 to the position shown in Figure 3, acting at the same time to secure the hammer in the locked position shown in Figure 3, so that a detonation of the cartridge in the barrel cannot occur, even if the pistol is accidentally dropped.

In case the pistol is to be put safe with the hammer in cocked position, see Figure 4, the nose *q* of the safety lever engages in the notch *l* of the hammer, see Figure 5, in order to lock the latter. At the same time the safety lever supports thereby the sear so that the double and consequently an absolutely reliable locking effect is ensured and the hammer is rigidly held in its locked position. The notch *q* of the hammer is so located that when the parts are in normal position, with the hammer uncocked and unlocked (Fig. 1) the nose *i* of the sear will project a slight distance into said notch, which latter is so shaped or recessed as to permit the movement of the hammer due to the pressure exerted upon it by the firing pin.

What I claim and desire to secure by the Letters Patent is:

1. In a recoil-loading pistol, the combination of a barrel, a grip-stock, a breech-slide, a rotatable hammer having a disk-like hub or nave, a sear engageable with said hub or nave, and a safety lever also mounted so as to engage with said hub or nave, said lever being operable at will from the outside to lock the hammer both in its cocked and in its uncocked position.
2. In a recoil-loading pistol, the combination of a barrel, a grip-stock, a breech-slide, a rotary hammer having a disk-like hub and a circular rib thereon, a sear engageable with said rib, and a safety lever also engageable with the rib, said lever being operable at will from the outside to lock the hammer both in its cocked and in its uncocked position.
3. In a recoil-loading pistol, the combination of a barrel, a grip-stock, a breech-slide, a rotatable hammer provided with a hub having a circular rib and a plurality of notches in said rib, a sear and a safety lever both engageable with said notches, said lever being operable at will from the outside to lock the hammer both in its cocked and in its uncocked position.

4. In a recoil-loading pistol, the combination of a barrel, a grip-stock, a breech-slide, a rotatable hammer provided with a hub having a circular rib with four notches therein, a sear mounted to engage in one or the other of two of said four notches, and a safety lever mounted in the handle and adapted to project into either of the two other notches.

5. In a recoil-loading pistol, the combination of a barrel, a grip-stock, a breech-slide, a rotatable hammer provided with a hub having a laterally extending circular rib and a plurality of notches in said rib, a safety lever engageable therewith, and a sear having a nose located within said circular rib and adapted to project into certain notches of said rib.

6. In a recoil-loading pistol, the combination of a barrel, a grip-stock, a breech-slide, a rotatable hammer provided with a hub having a circular rib with four notches therein, a safety lever mounted to engage one or the other of two notches, and a sear having a nose located within said circular rib and adapted to project into one or the other of the remaining two notches.

7. In a recoil-loading pistol, the combination of a barrel, a grip-stock, a breech-slide, a rotatable hammer having a circular hub provided with a notched circular rib thereon, a firing pin in said breech-slide, a sear engageable with a notch of said hammer rib, and a safety lever having one bevelled nose to engage another notch of the hammer rib for locking the uncocked hammer, the said lever being operable at will from the outside.

8. In a fire arm, a hammer provided on one face of its hub with a substantially annular, laterally-projecting rib having a plurality of notches formed therein, and a sear having a laterally-projecting nose which extends into the space within the rib for engagement with at least one of said notches.

9. A hammer for fire arms, provided on one face of its hub with a substantially annular, laterally-projecting rib having a plurality of notches formed therein, said notches extending in an outward direction from the inner face of the rib.

10. A hammer for fire arms, provided on one face of its hub with a substantially annular, laterally-projecting rib having four notches formed therethrough.

11. In a fire arm, the combination of a hammer provided on one face of its hub with a substantially annular, laterally-projecting rib having a plurality of notches, and a sear and a safety lever constituting companion parts both of which cooperate with said rib; one of said parts extending into the space within the rib so as to engage at least one of the notches from the inner side of the rib.

12. In a fire arm, the combination of a hammer provided on one face of its hub with a substantially annular, laterally-projecting rib having a plurality of notches formed transversely therethrough, and a member cooperative with said rib and having a part which extends into the space 15 within the rib and is engageable with at least one of the notches.
- 5 13. In a fire arm, the combination of a hammer provided on one face of its hub with a substantially annular, laterally-projecting rib having a plurality of notches

formed transversely therethrough, and a member cooperative with said rib and having a part which extends into the space 15 within the rib and is engageable with at least one of the notches.

In testimony whereof I affix my signature in presence of two witnesses.

JOSEF NICKL.
